United States Patent Office

Des. 188,113
Patented June 7, 1960

188,113

EASEL

Ray F. Morgan, Northfield, Ill., assignor to The Morgan Sign Machine Co., Chicago, Ill., a corporation of Illinois

Filed Jan. 25, 1960, Ser. No. 59,150

Term of patent 14 years

(Cl. D29—20)

I claim:

The ornamental design for an easel, as shown.
